Des. 238,325

Patented Jan. 6, 1976

238,325

ROOM DIVIDER

Nick J. Zorich, Jr., and Gregory B. Forsberg, both of
14625 15th Ave. NE, Seattle, Wash. 98155

Filed Feb. 11, 1974, Ser. No. 441,163

Term of patent 14 years

Int. Cl. D25—02

U.S. Cl. D6—139

FIG. 1

FIG. 2

FIG. 3

FIG. 4

FIG. 5

FIG. 1 is a front elevational view of a room divider showing our new design, the rear elevational view being identical;

FIG. 2 is a top plan view;

FIG. 3 is a bottom plan view;

FIG. 4 is a side elevational view of one side of the room divider; and

FIG. 5 is a side elevational view of the other side of the room divider.

We claim:

The ornamental design of a room divider, substantially as shown.
